Primary Examiner — Amy C Wierenga(74) *Attorney, Agent, or Firm* — The Concept Law Group, PA; Scott D. Smiley; Scott M. Garrett(57) **CLAIM**

The ornamental design for a urinal mat, as shown and described.

DESCRIPTION

FIG. 1 is a perspective view of a urinal mat showing my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a rear elevational view thereof.

The dash-dot-dash broken lines define the boundaries of the claim and form no part thereof. The evenly spaced broken lines shown in the drawings depict portions of the urinal mat that form no part of the claim.
